UNITED STATES PATENT OFFICE.

EDWARD H. BINNS, OF PITTSBURGH, PENNSYLVANIA.

DESK-LAMP.

1,174,962.

Specification of Letters Patent. Patented Mar. 14, 1916.

Application filed April 5, 1915. Serial No. 19,301.

To all whom it may concern:

Be it known that I, EDWARD H. BINNS, a citizen of the United States, residing at Woodland road, Pittsburgh, in the county of 5 Allegheny and State of Pennsylvania, have invented certain new and useful Improvements in Desk-Lamps, of which the following is a specification.

This invention relates to desk lamps and 10 more particularly to that type, which is adapted for position upon the top of roll or up-right desks, and in which the deflector overhangs the bed or writing surface thereof.

15 The primary object of the invention is to construct a lamp, of this character in a substantial and attractive form and at the same time render it of greater utility and less expensive than those now in use.

20 The invention consists in the provision of a lamp, having means for casting the rays of light over the writing bed of the desk and which has arranged therein a clock and thermometer, the latter being readily readable by the occupant of the desk.

25 A further object of the invention is to completely insulate the thermometer from the heat radiations of the lamp, by means of a non-conductive material disposed between 30 the thermometer and the lighting globe.

With this object in view, the invention 35 consists in the construction, combination and arrangement of parts hereinafter described in connection with the accompanying drawings, and will be more particularly pointed out and ascertained in and by the appended claims.

In the drawings, forming a part of the 40 application, Figure 1 is a front elevational view of my improved desk lamp. Fig. 2 is a longitudinal vertical section of the lamp, with the incandescent globe and desk in elevation, the latter being broken away.

The lamp as shown, consists of a hollow 45 body portion 1, which may be cast or otherwise formed of metal, or other suitable material, and adapted for position on the top or the rail of roll or upright desks. Formed 50 integral with the said body portion 1, and projecting outwardly therefrom, is the outwardly flaring deflector 2, which extends over a portion of the bed or writing surface of the desk, while the base 3, of the body portion rests on the desk top 4. The rear 55 wall 5, of the lamp body proper, is thickened

at its lower part as at 6, whereby the equilibrium of the lamp is maintained. The deflector 2, is apertured at 6, for the reception of the plug 7 into which is screwed the incandescent globe 8, which latter projects 60 downwardly at an angle within the said deflector, and a chain member 9, serves to operate the lamp. The wires 10, connecting the plug 7, with the source of electrical energy, passes through the hollow central portion of the lamp body, and through the opening 11, in the enlarged portion 6, of the rear wall 5 of the lamp body.

The lamp body proper extends upwardly 70 at 12, and the side-walls thereof, are provided with suitable ornamental scrolls 13. A circular opening is formed in the front face of the upper wall of the lamp body and a clock 14, is positioned therein, the said clock being wound and set from the dial face 75 thereof. The upper end of the lamp is provided with an interiorly threaded sleeve 15, and a thermometer 16, formed with a threaded shank 17, is screwed therein, surmounting the said lamp. The thermometer 16, is 80 of usual construction and positioned so that the temperature indications are easily read.

An asbestos casing 18, surrounds the clock, and serves to insulate the thermometer 16, from the heat radiated by the lamp, the said 85 insulation completely blocking the passage between the upper and lower hollow interior of the lamp body. The lower hollow portion of the lamp body may be filled with a suitable non-conductive material, such as asbestos, wool, etc. The base 19, of the lamp, is provided with an opening, and a suitable closure 20, seats therein, wherein admittance 90 is given to the hollow interior of the lamp body, for the insertion of the non-conductive 95 material, or for rewiring the lamp.

It is obvious that with a lamp of this construction, wherein the reflector projects out over the bed of the desk, and the lamp globe positioned at an angle, the light rays will be 100 diffused over the writing surface or central part of the desk. It is also obvious that the combination of an overhanging lamp, having a clock and a temperature indicator 105 therein, a useful as well as an ornamental article is assured, but it is to be understood that changes, variations and modifications can be resorted to, which may come within the scope of the claims hereinafter appended.

Having now described my invention, what I claim as new, is:

1. A lamp comprising a frame having a hollow base portion and upwardly extending spaced vertical rear and front walls, the front wall provided with an opening, a clock arranged in said opening, an asbestos casing surrounding said clock and completely blocking the passage between the top and bottom of the frame, the base portion of the said lamp being divided by a vertical apertured partition forming a deflector, an incandescent globe arranged in said partition aperture, said frame having its rear wall enlarged or thickened and provided with an opening, electric wires arranged in said last named opening and connected to said globe, said base being formed with a bottom opening communicating with the hollow interior thereof, whereby access may be had to the

wires and the clock casing, and a closure for said opening.

2. In a device of the type set forth, a hollow frame having a front lower lamp containing compartment, a rear lower wire receiving compartment for containing the feed wires for the lamp, and a top or dome compartment, which latter extends through the front wall of the frame and communicates with the rear lower compartment, said frame having an opening leading into the rear lower compartment, and a closure for the last named compartment.

25
30
In testimony whereof I affix my signature in presence of two witnesses.

EDWARD H. BINNS.

Witnesses:

RALPH DONATH,
J. SHAMBURG.
